Primary Examiner—Wallace R. Burke*Assistant Examiner*—Freda S. Nunn**[57] CLAIM**

The ornamental design for a second dimensional drive unit for X-Y slider, as shown and described.

DESCRIPTION

FIG. 1 is a slightly reduced top rear left side perspective view of a second dimensional drive unit for X-Y slider showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and

FIG. 7 is a left side elevational view thereof.

The broken lines are shown in FIGS. 1-3 for illustrative purposes only and form no part of the claimed design. The drive unit is used to move and support workpieces which are to be machined.
